UNITED STATES PATENT OFFICE.

HENRY C. WINEBRENNER, OF BALTIMORE, MARYLAND.

BILLIARD-CUE.

1,177,292.

Specification of Letters Patent. Patented Mar. 28, 1916.

Application filed October 14, 1915. Serial No. 55,758.

To all whom it may concern:

Be it known that I, HENRY C. WINEBRENNER, a citizen of the United States of America, and resident of Baltimore, Maryland, have invented certain Improvements in Billiard-Cues, of which the following is a specification.

This invention relates to improved means for securing the tip to the handle of a cue, 10 as will hereinafter fully appear.

In the further description of the said invention which follows, reference is made to the accompanying drawing, forming a part hereof, and in which:—

15 Figure 1 is an exterior side view of the end of a billiard cue provided with my invention, and Fig. 2 a central longitudinal section of the same without the handle. Fig. 3 is an exterior side view of the tip 20 and certain of the fastening devices. The handle of the cue is shown in broken lines.

Referring now to the drawing, 1 represents the handle of the cue, and 2 the tip which as usual in cues, is formed of some 25 slightly compressible material, such for instance as leather.

30 3 is a ferrule, the head *a* of which is made considerably thicker than its cylindrical wall, and provided with a central threaded hole *b*.

4 is a circular plate having on its under side a threaded stem *c* which is screwed into the hole *b* of the ferrule. The circular plate 4 is also provided on its upper side with an annular flange *d* which forms with the surface of the plate, a pocket *e* in which is inserted the tip 2. The fastening of the tip in the pocket *e* is effected by closing the edge of the flange *d* upon the compressible tip 2 as shown in the drawing.

40 I claim as my invention:

In combination with the handle of a billiard cue and its compressible tip, means to connect them which consists of a ferrule for the handle having a head with a central threaded hole therein, a circular plate with a cylindrical threaded pin adapted to be screwed into the said hole and having an annular flange the edge of which is crimped inward to grasp the tip and form a circular indentation therein and thereby hold the tip closely in contact with the said circular plate.

HENRY C. WINEBRENNER.
